UNITED STATES PATENT OFFICE.

HARLAN P. WELLS, OF AMESBURY, MASSACHUSETTS.

DESIGN FOR A VEHICLE-AXLE.

SPECIFICATION forming part of Design No. 31,980, dated December 12, 1899.

Application filed November 10, 1899. Serial No. 736,550. Term of patent 14 years.

To all whom it may concern:

Be it known that I, HARLAN P. WELLS, a subject of the Queen of Great Britain and Ireland, residing at Amesbury, in the county of Essex and State of Massachusetts, have invented and produced a new and original Design for a Vehicle-Axle; and I do declare the following to be a full, clear, and exact description of the same, reference being had to the accompanying drawings, forming a part thereof.

Figure 1 is a view in perspective of a vehicle-axle, showing my new design. Fig. 2 is a sectional view taken on a line about midway of the ends of the axle.

As shown by the figures of the drawings, the leading or characteristic feature of my design resides in the peculiar sectional shape of the body of the axle or that part which lies

A A are the axle-spindles, and B B the collars. The top surface D and the bottom surface E of the body of the axle are flat, as shown. The sides F F are curved surfaces, as clearly indicated in the sectional view, 25 each curved surface extending from the flat top to the flat bottom surface.

Having described my invention, what I claim as new, and desire to secure by Letters Patent, is—

The design for a vehicle-axle, substantially as herein shown and described.

In testimony whereof I affix my signature in presence of two witnesses.

HARLAN P. WELLS.
